CIRCULATING TYPE PACKER AND
VALVE THEREFORHerbert Allen, Houston, Tex., assignor to Cameron
Iron Works, Houston, Tex., a corporation of
Texas

Application August 20, 1943, Serial No. 499,393

10 Claims. (Cl. 166—10)

1

This invention relates to a circulating type packer and valve therefor.

This application is a continuation-in-part of my prior co-pending application Serial No. 291,180, filed August 21, 1939, for Tubing packer.

For the purpose of packing off the space between the tubing and casing of a well there is provided a sealing means known as a packer, and these ordinarily consist of some deformable packing material surrounding the tubing and of some means for compressing the packer material in an axial direction so as to cause it to expand laterally and engage the casing to form a seal between the tubing and the casing. In order to cope with the high pressures frequently encountered it is necessary that the rigid annular members employed as abutments at the opposite ends of the packing material have a relatively very small clearance within the casing because if a large clearance is left, high pressures may cause the packing to be extruded from its proper position, forced out of place and destroyed. With such relatively small clearances left around the outside of the packer, it has been found necessary to provide what is known as a circulating type packer having a passageway or passageways up through the interior of the packer in order to permit fluid to flow past the packer as the device is lowered into a casing, in order to permit fluid to be returned up around the outside of the tubing while the well is being washed by pumping down through the tubing, and in order to permit the well to be flowed through the casing if that should become desirable at any time; and to provide some means whereby this passage through the packer may be closed so as to provide a complete closure between the tubing and the casing. Considerable difficulty has been encountered in providing a structure which would afford adequate passage for fluid to thus flow through the packer, and in providing at the same time an effective closure for such passage.

It is a general object of this invention to provide an improved circulating type packer and an improved valve for closing the passageway therethrough.

Another object of this invention is to provide a construction of the type referred to which is relatively simple and capable of trouble-free operation.

Another object is to provide a device of the class described in which the passages through the packer are sufficiently large that the throttling of liquid within the device is avoided.

Another object is to provide a device in which

2

effective sealing of the valve is assured even though the valve seat or other corresponding parts may have been damaged by circulation of fluid through the packer.

5 Another object is to provide a self-sealing valve for closing the passage through the packer.

Another object is to provide a valve having a self-sealing packing for closing the passage through the packer in which the self-sealing 10 packing will be prevented from being extruded and destroyed either under mechanical or fluid pressure.

Other objects and advantages of this invention will become apparent from the following description of the drawings forming a part of this application wherein is disclosed one embodiment of the invention.

In the drawing:

Fig. 1 is a vertical sectional view through a 20 device embodying the invention.

Fig. 2 is a sectional view similar to that shown in Fig. 1 but showing the relative position of parts when the packer is set and the circulating passage therethrough is closed.

25 Fig. 3 is a sectional plan view taken on the line 3—3 of Fig. 2.

Fig. 4 is a sectional plan view taken on the line 4—4 of Fig. 2.

30 Fig. 5 is a perspective view partly in section showing the valve sealing assembly which constitutes an element of the invention.

Referring more in detail to the drawings, there is shown a circulating type packer and valve therefor constructed in accordance with this invention and adapted to form a seal within a casing

35 1. This circulating type packer is generally indicated at 2 and is carried on a tubing 3 through which it may be desired to wash or flow the well.

40 Threaded to the lower end of the upper section of tubing or flow string 3 is a valve composed of a valve cage 4 having a counterbore 5 therein adapted to receive a valve sealing assembly 6. This assembly has a bore 7 therein through which

45 extends the upper end of a tubular member or extension 8 forming an extension of the upper section of the tubing or flow string 3. This tubular extension 8 is threaded into the valve cage 4 so that its interior will be in communication with the interior of the upper tubing section 3,

50 and spaced slightly below the open end of the counterbore 5 is provided with a laterally extending portion providing an upwardly facing shoulder adapted to engage the lower or outer end of the valve sealing assembly 6 and hold it in place within the counterbore 5.

The tubular extension 8 extends downwardly through the packer 2 and the packer is retained thereon by means of lugs or stops 15 spaced peripherally about the exterior of the section 8 and adapted to engage the lower end of a mandrel 16 on the upper end of which is carried the packer head 17 having a valve seat 18 thereon for a purpose presently to be described.

Surrounding the mandrel 16 below the packer head 17 are resilient packer rings 20 which are separated by a spacer ring 21. A packer retainer ring 22 slidably surrounds the mandrel 16 below the lowermost packer ring 20 and is held in place upon the mandrel by means of a short sleeve 23 attached to the mandrel and having an internal bore of sufficient diameter to expose the end of the mandrel and present a shoulder 24 against which the stops 15 may abut. Thus the entire packer assembly may be suspended upon the tubular extension 8 and its downward movement thereon will be limited.

Threaded to the retainer ring 22 and extending downwardly therefrom around the short sleeve 23 is a nipple 30 having perforations 31 there-through of desired size and number to accommodate the flow which it is intended for the packer to permit when its valve is in open position. This nipple 30 is threaded at its lower end to a special coupling 32 which is recessed internally to receive a seal ring 33 through which the lower end of the section 8 slidably extends. A seal is thus formed to prevent the passage of fluid between the coupling 32 and the outside of the section 8. A compression spring 34 is interposed between the sleeve 23 and the coupling member 32 to exert a force which tends to keep said sleeve and coupling member in spaced relation.

A tubing nipple 35 is connected to the lower end of the coupling 32 and has an internal bore sufficiently large to receive a collar 36 carried on the lower end of the section 8. This collar has radially extending keys 37 longitudinally thereof and these keys slidably fit within keyways 38 in the interior of the nipple 35 to provide a slideable but non-rotatable connection between the nipple 35 and the extension 8.

In the form illustrated in the drawing a reducer coupling 40 is attached to the lower end of the nipple 35 and is connected to an anchor pipe 41 which extends to the bottom of the well. The threaded connection 42 between the anchor pipe and the coupling 40 may be either a right or a left-hand connection. It is preferable, however, that a left-hand thread be provided in this connection so that if desired or necessary the device may be unthreaded at this point by rotating the tubing or flow string 3 right-handedly so as to avoid the disconnection of other couplings in the string.

It is to be understood that the anchor pipe 41 will be of such length that the packer will be positioned at the desired level within the well. It is also to be understood that this pipe may include either a liner and screen or a permanent packer setting or may merely be a perforated pipe for production tests.

Reference is now had particularly to Fig. 5 wherein is shown a self-sealing type of sealing assembly 6 for the valve which is adapted to close the passage down through the packer 2. This valve sealing assembly 6 in the form illustrated consists of a ram assembly 45 made up of two concentric annular ram elements preferably though not necessarily joined together at inter-

vals by integral connecting parts extending between them, together with a body of soft resilient and flowable sealing material such as rubber. The two annular ram elements provide an annular space 46 between them, this space 46 being interrupted only by the small connectors which serve to interconnect the annular ram elements. The ram elements terminate at their lower or outer ends in tapered annular seating surfaces 48 adapted to seat against the valve seat surface 18 on the packer head 17. Interposed between these annular ram elements and terminating at one end in a surface forming substantially a continuation of the seating surfaces 48 is a body of packing or sealing material 50 which may be molded or otherwise put in place between these two elements. This body of packing material 50 extends beyond the upper or inner ends of the ram elements and overlies them with a substantial body of packing material as shown at 51. The packing material employed may be rubber or some similar material soft enough to form the desired seal and sufficiently fluent to flow under pressure.

It will be seen that when the valve sealing assembly 6 illustrated in Fig. 5 is in place within the counterbore in the valve cage 4 as illustrated in Figs. 1 and 2, it will be held in place by the shoulder 9 on the tubular extension 8. When this valve cage 4 is moved downwardly so that the ram elements contact the valve seat 18 along the surfaces 48, the ram assembly will be forced further into the counterbore in the valve cage 4. When this occurs, the portion 51 of the body of sealing material will be put under pressure and the body of sealing material will be urged by this pressure to flow outwardly through the annular space between the ram elements. This will cause it to exert a greater pressure against the valve seat 18 between the ram elements and thus effect a seal. This seal will be effected even though the valve seat 18 may have been somewhat damaged or even though there may be minor obstructions thereon, because the pressure of the ram assembly against the packing material will cause it to fill minor cutout portions in the seat and to flow around any minor obstructions on the seat. At the same time, however, the two ram elements will serve as inner and outer dams to prevent the sealing material from being forced laterally in either direction by pressure of fluid tending to flow through the packer or by the pressure produced in the sealing material 50 by the rams themselves.

It will thus be seen that a valve means has been provided which is capable of effectively closing the flow passage through packer 2 even though the valve seat may have been damaged or may be obstructed, which closure will at the same time be capable of effectively resisting relatively high operating fluid pressures.

Attention is directed to the fact that the passage through the mandrel 16 is relatively large. Hence in assembling the device the shouldered upper end 9 of the section 8 may be passed therethrough before connection is made with the valve. The principal utilitarian value of this feature, however, resides in the fact that large passages are provided for the by-passing of liquid during the descent of the device into the well or during the washing or producing of the well.

It is believed that the operation of the device is apparent from the foregoing description but it is noted that when using the device illustrated, a correct length of anchor pipe 41 is first at-

tached to the lower end of the packer. The device is then run into the well on the flow string 3 until the anchor pipe contacts the bottom of the hole. It will be understood, however, that the device may be anchored in any other suitable manner. The well may then be washed any desired amount, the openings 31 in the nipple 30 permitting the washing fluid to pass freely into and through the mandrel 16. Tendency of the packer to set under the pressure of the washing fluid is thus minimized by reducing the pressure drop between the lower and upper extremities of the packer.

When washing is completed the tubing or flow string 3 is lowered so that the valve sealing assembly 6 contacts the seat 18 on the head 17 and moves the head 17, mandrel 16 and sleeve 23 downwardly against the compression of the spring 34. Since the packer retainer ring 22 is anchored against downward movement, this downward movement of the head 17 and associated parts compresses the packer rings 20 in an axial direction and causes them to expand laterally into sealing engagement with the casing 1 as is clearly shown in Fig. 2.

As has been explained, the ram elements forming a part of the valve sealing assembly 6 will contact the valve seat 18 thus forcing the ram assembly provided by these elements further into the counterbore 5 and urging the sealing material 50 to flow outwardly and downwardly through the annular space between the ram elements and into tight sealing engagement with the valve seat 18.

It will be understood that the device set forth in the foregoing description and the accompanying drawings is by way of illustration and example only and that this invention is not to be construed as limited thereby.

Having described my invention, I claim:

1. In a device of the class described, a packer including a head having an upwardly facing seat thereon, a tubing string and a valve on said tubing string movable with said string to engage said seat and control the discharge of fluid through the head about the tubing string, said valve comprising a valve cage removably connected in the said string and an annular valve sealing assembly fitting telescopically therein, said annular assembly including substantially rigid parts providing an annular downwardly opening channel therein, and a body of resilient material confined and filling the spaces between the valve cage, said parts and the tubing string, and filling said channel.

2. In a device of the class described, the combination of a flow string, said flow string including upper and lower telescopically connected sections, a packer surrounding the upper section and providing an annular passage between itself and the upper section, an upwardly facing valve seat on the upper end of the packer, a valve member carried by the upper section of the flow string and adapted to engage said seat, a packing retainer ring on the lower end of the packer and a perforated tubular connection between the lower section of the flow string and said ring.

3. In a device of the class described, a flow string including upper and lower telescopically connected sections, a packer surrounding the upper section in spaced relation to and longitudinally movable relative thereto and including a mandrel, an upwardly facing valve seat on the upper end of the mandrel, a valve member carried by the upper section of the flow string and

adapted to engage said seat, expansible packer means on said mandrel, a packer retainer ring movably mounted on said mandrel below said packer means, a perforate tubular connection connected to between said ring and the lower section of the flow string providing a telescopic connection between the mandrel and the lower section, spring means normally urging the mandrel and lower section to extended position and a shoulder on said mandrel engageable with said ring to prevent separation of said mandrel from said tubular connection.

4. In a device of the class described, a flow string including upper and lower sections telescopically interconnected at their adjacent ends, a fluid excluding seal between said sections whereby well fluid is directed continuously through said sections, a packer surrounding the upper section in spaced relation thereto and including a mandrel, an upwardly facing valve seat on said mandrel, a valve member on the upper section adapted to engage said seat, expansible packer means on said mandrel, means movable on said mandrel to expand said packer means, and a perforated tubular connection between the lower section of the flow string and said means movable on the mandrel whereby fluid arising about the lower section may enter and pass upwardly through the annular space between the mandrel and the upper section outwardly of the device when the valve is lifted from its seat.

5. In a device of the class described, a flow string comprising upper and lower telescopically connected sections, a packer surrounding one section and in annular spaced relation therewith, said packer including expansible packer means and relatively movable parts to effect expansion thereof, a valve seat member on said packer, a valve member carried by said one section and adapted to engage said seat member and a perforate tubular connection between the packer and the other of said sections so that telescopic movement of the sections first closes the annular passage through the packer and thereafter expands the packer means.

6. In a device of the class described, a flow string comprising upper and lower telescopically connected sections, a sleeve attached to one of the sections and extending outwardly about the other section, a packer surrounding said other section in annular spaced relation therewith and including relatively movable parts and expansible packer means adapted to be expanded thereby, one of said parts being attached to said sleeve, the other of said parts including a valve seat, and a valve carried by said other section and engageable with the valve seat to close the annular space between the packer and flow string and thereafter expand said packer means.

7. In a device of the character described, an annular head, an upwardly facing valve seat thereon, a valve adapted to engage said seat and comprising a cage having a passageway therethrough and a counterbore therein, a tubular extension attached to the cage and extending downwardly from within the counterbore, a shoulder on said extension, and an annular valve sealing assembly within the counterbore surrounding said extension and in engagement with and retained in place by said shoulder.

8. In a device of the character described, an annular head having an upwardly facing valve seat thereon, a valve adapted to engage said seat and comprising a valve cage adapted to move axially of said head, said valve cage having a pas-

sageway therethrough and a counterbore, a tubular member secured to the cage within the counterbore, a shoulder on said member, an annular valve sealing assembly within the counterbore, surrounding said tubular member and engaging said shoulder, said shoulder retaining the assembly in the counterbore, said valve sealing assembly comprising an openwork ram assembly having an annular downwardly opening groove in the lower face thereof, and a body of resilient material molded into said ram assembly.

9. In a device of the character described, in combination with a packer having a head with an upwardly facing seat thereon, and a flow string having a section extending within said packer, a valve on said flow string to engage said seat and control the discharge of fluid through the head about the flow string, said valve comprising an annular valve cage having a passageway therethrough and a counterbore in one end thereof, a valve sealing assembly in said counterbore about said flow string, said valve sealing assembly comprising a ram of smaller cross section than said counterbore and lying partly within said counterbore and spaced from the inner end thereof, and a body of resilient material filling said counterbore except for the space occupied by said ram, whereby when said valve is closed against the valve seat said ram will encounter the valve seat and be forced further into said counterbore, thereby urging said resilient material to seal more tightly between said cage and flow string and to flow outwardly and seal more tightly against the valve seat.

10. In a device of the class described, in combination with a packer having a head with an upwardly facing seat thereon, and a flow string having a section extending within said packer, a valve on said flow string to engage said seat and

control the discharge of fluid through the head about the flow string, said valve comprising a valve cage having a passageway therethrough and a counterbore in one end thereof, and a valve sealing assembly in said counterbore about said section of the flow string, said valve sealing assembly comprising spaced inner and outer annular rams lying partly within and projecting partly from said counterbore and spaced from the inner end thereof, and a body of resilient material confined between said rams and extending into the space within said counterbore inwardly of said rams, whereby when said valve is moved against the valve seat said annular rams will engage the valve seat and will be moved thereby further into said counterbore, thus urging said resilient material to flow outwardly between the rams and to more tightly engage the seat.
